UNITED STATES PATENT OFFICE

HERMAN S. LYSTER, OF INDIANAPOLIS, INDIANA

PARCEL REMOVER FOR MAIL BOXES

Application filed October 23, 1929. Serial No. 401,898.

This invention relates to mail boxes designed to receive parcels from mail carriers for individuals or others, especially at residences, the invention having reference more particularly to a mail box appliance that is adapted to be used for conveniently and expeditiously removing postal parcels from a mail box, particularly the smaller size from boxes designed to receive the large sizes of envelopes or parcels.

An object of the invention is to provide improved facilities for delivery of mail matter to parties addressed, more particularly to such parties as maintain mail boxes at their premises to receive parcels from postal carriers, whether in cities or towns or on rural routes.

Another object is to provide a device whereby parcels may be lifted so as to be conveniently and easily reached and drawn from a mail box which may have considerable depth so as to make it difficult to reach into by hand, especially to withdraw the smaller letter sizes.

A further object is to provide an improved parcel remover that may be adapted to conform to different sizes of mail boxes, adapted to be manufactured at small cost and be convenient in use, durable and economical.

With the above-mentioned and other objects in view, the invention consists in a parcel remover of novel construction for application in a novel and useful manner to a mail box whereby to draw parcels therefrom; the invention consisting also further in the parts and combinations and arrangements of parts as hereinafter particularly described and further defined in the claims appended hereto.

Referring to the accompanying drawings,—Figure 1 is a front view of a mail box having the invention applied thereto; Fig. 2 is a vertical central section of Fig. 1; Fig. 3 is a rear elevation of the parcel remover; Fig. 4 is a rear elevation of one part and Fig. 5 a rear elevation of the main part of the remover and, Fig. 6 is a horizontal section and plan of the remover.

Similar reference characters in the various figures of the drawings indicate corre-

sponding elements or features of construction herein referred to in detail.

As preferably constructed the parcel remover is designed to constitute a movable part of a mail box which may be variously patterned, the remover being adapted to be applied to existing mail boxes and preferably is made adjustable to conform to different sizes and shapes of boxes. For descriptive purposes the remover is shown in connection with a common upright type of mail box extensively used on the front of dwellings and elsewhere, the box comprising a back plate 1 by which the box may be supported, a bottom 2, sides 3 and 4 and a front 5 having a recess 6 in its upper portion that is covered by a lid 7 which extends over the tops of the sides and has a hinge connection 8 with the back plate, the upper portion of the lid having a slot 9 therein to receive mail matter from carriers. The slot is provided with a shutter 10 connected with the hinge 8. The lid 7 is provided with a hasp 11 to enter a slot 12 in the front of the box, there being a lock case 13 secured on the inner side of said front and having a lock bolt 14 to engage the hasp, the lock having a key barrel 15 projecting through said front. The front of the box usually has a number of peep-holes 16 therein through which to conveniently ascertain whether or not any mail matter may have been deposited in the box.

In carrying out the objects of the invention, the mail box of the character above-mentioned, whether for town or rural mail, is provided with a movable lifting device adapted to be pulled by hand to draw parcels up from the mail box. For a mail box of the type above-described in detail, a remover is provided that is adapted for lifting parcels upward in the box sufficiently high to be conveniently reached and taken by hand from the upper portion of the box. Accordingly the remover comprises a main part having a pocket on its lower end and a handle on its opposite upper end. The remover preferably is adjustable to correspond with different widths of boxes already in use; for such particular purpose the main part comprises two body portions or parts 17 and 18 having

5 pocket bottom portions 19 and 20 respectively, the portions 20 having slots 21 therein to receive a tongue 22 that projects from the opposite bottom portion 19 to lock the two portions together when one is placed upon the other. The parts 17 and 18 are placed in overlapping arrangement, one part having slots 23 to receive a tongue 24 that projects from one edge of the other of the two parts 10 whereby to adjustably secure the parts together. The bottom portions of the pocket have low wall portions 25 and 26 respectively and also end walls 27 and 28 respectively that are connected with the parts 17 and 18 respectively and also the low wall portions that are arranged together at the inner side of the back plate 1 of the mail box, the wall portions being flared so as to closely fit at their tops against the back plate of the box to prevent thin parcels from slipping past the pocket when descending in the box, the bottom of the pocket normally resting upon the bottom 2 of the mail box while the main portion of the remover extends upward behind 25 the front 5 of the box and affords a guide to prevent parcels from lodging on the locking apparatus inside the box. The part 18 has a rounded top 29 designed to prevent parcels entering the box from catching thereon. The 30 part 17 has a handle 30 on its top that extends beyond the top 29 and slightly forward so as to be easily accessible through the recess 6 and preferably is provided with a ring 31 connected to the upper portion of the handle 35 by means of a suitable loop 32. Each part 17 and 18 preferably has window openings 33 therein to permit mail matter in the box to be seen through the peep-holes 16.

40 In practical use, the mail box customarily is locked, the postman or letter carrier placing parcels in the box through the slot 9 in its top, the parcels fall into the pocket of the remover. When the person having a key to the mail box desires to remove the mail matter the lid 7 after having been unlocked is lifted and the handle 30 readily taken hold of and pulled upward until the pocket of the remover lifts the parcels sufficiently high to be easily taken therefrom and from the top 45 50 of the box, after which the remover is returned by lowering it to its usual place in the box.

What is claimed is:

- 55 1. A parcel remover for mail boxes including a plate-like body and a pocket composed of two parts having each a body portion and a pocket portion, the parts being adjustably connected together and one of the parts having a handle projecting from the body portion, the pocket portions having each a bottom.
- 60 65 2. A parcel remover for mail boxes comprising two plates arranged adjustably each to the other and secured together and having two co-operating pocket parts fixed to

the plates respectively at one side of one end portion of the plate, the pocket parts having each a bottom portion and being secured together, one of the plates having a handle on its opposite end projecting therefrom and beyond the end of the other of the two plates. 70

3. The combination of a mail box and a parcel remover vertically movable therein comprising a body plate and a parcel pocket on one side of one end portion of the plate, 75 the plate having a handle on the opposite end portion thereof, the pocket having a bottom and being adapted to receive parcels and to draw them up in the box from the deeper portion of the box by means of said body plate and said handle. 80

4. A parcel remover for mail boxes adapted to be lowered through the top to the bottom of the box, the remover comprising a plate-like body and a bottom portion extending from the lower end of the body adapted to removably rest upon the bottom of a mail box, the bottom portion having a low front wall portion flared to engage the back of the mail box and having also end walls constituting a pocket on the lower end of the body, the body being adapted to guide parcels downward into the pocket and to lift the pocket and parcels upward in the box, the upper portion of said body being relatively 90 narrow and curved outward to constitute a handle and a guide portion adjacent to the front of the mail box, and a ring loosely mounted on the outer side of said handle and guide portion to lift said remover. 100

In testimony whereof, I affix my signature on the 16th day of October, 1929.
